HAND LOOM

Keith J. Smith, Alhambra, Calif., assignor to
Calcraft Company, Pasadena, Calif., a corpora-
tion of California

Application July 15, 1949, Serial No. 104,824

14 Claims. (Cl. 28—15)

1

This invention relates to hand looms of that type which embodies a rectangular frame provided with upstanding weaving pins on each side rail thereof around which is looped a thread or yarn, the latter being first carried back and forth to extend between the pins of opposite rails and then passed back and forth between the pins of the other opposite rails of the frame, after which by the aid of a needle the yarn is interwoven with the initially arranged crossed rows of the yarn to weave a selected design.

It has heretofore been the practice to construct hand loom frames from four sections of wood, the ends of the sections being connected by mitered or rabbeted joints at the corners. Metallic pins have been driven in rows along the side members or rails to provide the series of upstanding weaving pins around the frame. Such conventional hand looms are subject to several disadvantages, one of which is that they are expensive to manufacture, it being apparent that the joining of the side rails and the insertion of the weaving pins are costly production operations. Another disadvantage resides in the fact that unless heavy, hard and expensive wood is employed, it is quite apt to splinter, due to rough usage, and this is detrimental for the reason that the minute filaments of the yarn or thread may catch on such splinters and thus become broken. Moreover, the wire pins used in conventional hand loom frames are smooth and slippery so that the loops of yarn extending therearound are easily displaced therefrom and it frequently becomes necessary to retrieve the loops and reengage them on the pins. It is thus apparent that such conventional hand loom frames are quite impractical, both from the manufacturing and operational standpoints.

Various attempts have been made to overcome the deficiencies of conventional hand loom frames, one such improved frame being molded from plastic material but having steel weaving pins secured to the frame. Another proposed frame is made from wood and each side rail of the frame supports a fiber bar which has a series of integral teeth. While such fiber teeth are more efficient in retaining the loops of the yarn in place, they may be relatively weak and become easily broken. Moreover, such fiber bars of teeth are rather unattractive and, as will be apparent, unless a positive means is provided for securing the bars in place, they are apt to become disassembled and lost. If fastening devices are employed, the assembly operation is complicated and the manufacturing cost of the article is materially increased.

2

Fabric woven on hand loom frames is usually made in four-inch squares and these squares are thereafter joined together to make a fabric piece of any desired size and shape. It is often desirable, however, to fabricate rectangular pieces of smaller dimensions, that is, pieces which are 2" x 4", 3" x 4", 2" x 2", etc., such small rectangles being used as fillers and as pieces for shaping the garment or other fabric article being

10 made. It has been proposed in the past to employ a crossbar adapted to extend across the frame of the loom and having a series of pins thereon corresponding in number to that of a side rail of the frame. The ends of the crossbar are 15 selectively engageable with the pins of opposite side rails so that the bar can be adjusted toward and away from a third side rail to cause its pins to cooperate with the pins of said third rail.

While the use of such a crossbar permits the 20 making of rectangular pieces, such pieces must have a length equal to the full width of the frame, for example, four inches, and it is impossible to weave squares having sides smaller than four inches. The crossbars referred to above are 25 rather awkward to place on the frame and unless extreme care is exercised during such assembly, the pins of the side rails are apt to become bent. In another prior loom device opposite side rails are provided with slits on their inner surfaces for 30 receiving the ends of the crossbar to frictionally retain the bar in place on the frame. It has been determined that such retaining means is inefficient and the bar is frequently inadvertently pushed through the frame, thus releasing the 35 threads being woven.

It is an object of this invention to obviate the 40 deficiencies of the prior hand looms discussed above by providing a loom frame which is molded in a single piece from plastic material, the weaving pins or teeth being molded integral with the frame. By this construction, a highly efficient, serviceable and attractive loom frame is provided and, since finishing and assembly operations are eliminated, the article can be made at a fraction 45 of the cost of producing conventional loom frames where machining and assembling of components are necessary.

Another object is to provide a device, of the 50 character referred to, in which the integrally molded weaving pins or teeth are made smooth, that is, free from corners which might tend to damage the small filaments of the thread being woven. Another object in this respect is to provide weaving teeth which have laterally and outwardly projecting protuberances at their upper 55 free ends, these projections serving effectively to

retain the thread or yarn loops in place on the teeth to guard against displacement thereof, thereby eliminating the necessity of extending the teeth too high, in order to retain the loops satisfactorily, and also eliminating interference with weaving operations.

A further object is to provide a hand loom frame which is especially strong and durable, the side rails having a channel-shaped cross-section so as to provide adequate strength and rigidity.

Another object is to provide a device of the type indicated in which the upstanding pins or teeth have portions which extend downwardly from the upper edges of the side rails along the sides thereof to provide markers by which the loops of yarn can be readily counted.

A further object is to provide a hand loom which includes a plurality of crossbars adapted to be inserted into the frame and to extend transversely thereof, the crossbars being molded from plastic material and having integral, longitudinally spaced, upstanding pins or teeth of the same form, size and spacing as the teeth of the side rails of the frame. By this provision, the interior of the loom frame can be divided into rectangles of desired sizes so as to adapt the device for producing small woven rectangles of differing sizes to be used as fillers or shaping pieces in a woven article. In accordance with my invention, there is provided a crossbar having a length substantially equal to the inside dimension of the square frame and by inserting this bar in the frame, rectangles having one of their dimensions equal to the width of the frame and their other dimension equal to a portion only of the width of the frame can be produced as desired. It is a further object in this respect to provide an additional or auxiliary crossbar which can be installed in the frame to extend from the main crossbar to a side of the frame which extends parallel to the main crossbar so that the division made by the main crossbar can be readily subdivided to provide relatively small squares. By this means, it is possible to produce a large variety of sizes of woven pieces and the device is thus rendered more universal in use.

A still further object is to provide in a hand loom means for mounting the crossbars in place in the frame. In accordance with the concept of this invention, the inner sides of the side rails of the frame are provided with narrow vertical openings or sockets for receiving the narrow ends of the crossbars which are merely lowered thereto. As a feature of improvement, the openings do not extend clear through the material of the side rails so that there are provided ledges or seats at the bottom of the openings upon which the ends of the crossbars rest to be fully supported. The side rails may have any suitable number of the openings, preferably spaced apart in multiples of inches, so that by placing the ends of a crossbar in the appropriate openings, the interior of the frame can be quickly divided into rectangles of say, 2" x 4", 1" x 4" and 3" x 4". The auxiliary crossbars are employed when it is desired to produce squares which are smaller than the maximum 4" square, such as 2" squares and 3" squares. Such small squares are readily produced by causing an auxiliary crossbar to extend between the main crossbar and a side rail of the frame. To facilitate such an adjustment, the main crossbar is provided with one or more vertical openings and seats in at least one side thereof, these openings being adapted to align with the corresponding openings of a side rail of

the frame. By this means, the ends of an auxiliary crossbar can be inserted in such aligned openings to subdivide the interior of the frame into small squares of desired dimensions, and this is a further important object of the invention.

Further objects of my invention will be apparent from the following description and from the drawing, which is intended for the purpose of illustration only, and in which:

Fig. 1 is a perspective view of my improved hand loom;

Fig. 2 is a plan view thereof;

Fig. 3 is an enlarged cross-sectional view, taken on line 3—3 of Fig. 1;

Fig. 4 is a cross-sectional view, taken on line 4—4 of Fig. 3;

Fig. 5 is a cross-sectional view through a side rail of modified form;

Fig. 6 is a cross-sectional view through a cross-bar of slightly modified form; and

Fig. 7 is a diagram illustrating the various ways of dividing the frame to produce a wide variety of woven pieces.

Referring to the drawing in detail, my improved hand loom includes a square frame 10 which is molded from a plastic material having relatively great strength and possessing high luster besides being especially attractive in appearance. The frame 10 comprises four integral side rails 11, 12, 13 and 14 which preferably are of the channel shape shown in Fig. 3 to provide adequate strength while maintaining the weight of the frame at a low value. By this shape, the side rails have outer vertical sides 15 and inner curved support portions 16. If preferred, however, the rails may be made solid as shown in Fig. 5 and yet retain the same outer contour.

Molded integrally with the rails are upstanding weaving pins or teeth 20 which are preferably of substantially circular cross section to avoid corners which might tend to cut the delicate filaments of the thread or yarn being woven. At their upper ends, the teeth 20 are provided with laterally and outwardly projecting protuberances 21 which are preferably conical in outline and transverse to the side rails. As will be apparent, such enlargements serve as stops to limit the upward sliding movement of the yarn which is looped around the pins 20, so as to prevent unwarranted displacement of the yarn. After the piece of fabric has been woven, however, the loops of yarn or thread can be stretched slightly over the enlargements to free them from the weaving pins. To facilitate counting the loops of yarn in the fabric being woven so as to aid in producing the desired pattern, means are provided for indicating the numbers of the loops. As shown in the drawing, the teeth or pins 20 have their lower ends disposed alongside and forming part of the vertical walls 15 of the side rails 11, 12, 13 and 14. These ends of the pins 20 thus provide, in effect, vertical ribs 22 which serve as indicator marks by which the pins can be conveniently counted. To further aid in the counting, the ribs 22 may be of different lengths as illustrated best in Fig. 1. For example, every third rib may be made longer than the other ribs.

As thus far described, the hand loom frame 10 is applied to use in the same manner in which conventional frames are employed, the procedure involving the anchoring of an end of a length of yarn 23, shown in broken lines in Fig. 2, in a slit 24 in a side rail and looping the yarn alternately

around the weaving pins 20 of the several side rails in the usual manner to form the warp threads after which yarn is interwoven, by means of a needle, with the crossing rows of the warp threads to produce a fabric of the desired pattern. If the square defined by the rows of pins 20 of the several side rails measures 4", then the finished piece of fabric will also be a 4" square. The completed squares can be later joined to produce the desired fabric article or may be woven continuously in long lengths by removing a finished square from the frame, hooking the loops at one of its sides to a row of the pins 20, re-threading the loom frame and interlacing the loops of the previously made square with those of the square being produced, this being a common procedure. It is sometimes desirable to produce relatively small rectangles and squares of the woven fabric to be used as fillers or forming pieces or to be incorporated in a blanket, afghan, or the like to produce a desired over-all pattern. My invention provides means by which pieces smaller than the full area of the frame can be readily produced. As will be apparent, in order to make such small pieces, the effective working area of the frame must be reduced. Such reduction or subdividing is accomplished by means of crossbars, to be later described. For the purpose of mounting the crossbars, the inner curved support portions 16 of the several side rails of the frame 10 are provided with relatively narrow, vertical openings or sockets 25. These openings do not extend clear through the material but rather end short of the bottom surface of the frame so as to provide horizontal rests or seats 26.

A main crossbar 30 is molded from plastic material and is substantially cruciform in cross-section as shown best in Fig. 4. At its end portions, the horizontal arms of the cross are omitted so as to adapt the end portions to be received in the vertical openings or sockets 25 of the side rails of the frame 10 and to rest upon the seats 26 of the sockets as shown in Figs. 1 and 3. Intermediate its ends, at least one side of the crossbar 30 is extended laterally in a curved portion 31 which is provided with narrow, vertical openings 32 having horizontal seats 33 at their lower ends, these openings being similar to the openings 25 previously described.

The crossbar 30 is also provided with vertically projecting weaving pins or teeth 35 which are similar to and are spaced apart a distance corresponding to the teeth 20. The openings 25 are so spaced relative to the ends of the side rails 11, 12, 13 or 14 that when the crossbar 30 is disposed with its ends in one pair of opposite openings it defines, with the side rails, a rectangle which measures 3" x 4" and a second rectangle which is 1" x 4", this relationship being illustrated in Figs. 1 and 2. When the crossbar 30 is disposed with its ends in openings 25 arranged at the centers of opposite side rails, it divides the frame 10 into a pair of rectangles which measure 2" x 4".

In order to subdivide the frame 10 into areas of even smaller dimensions, the present invention contemplates the use of one or more auxiliary crossbars, such as the one indicated generally at 40 in Fig. 2. The auxiliary crossbar 40 has weave pins 41 and is similar to the crossbar 30 except that it has no socket openings. The ends of the auxiliary crossbar 40, which is approximately 2" long, are adapted to fit in the openings 25 and 32 of the respective side rails and crossbar 30 and when so disposed in the frame it may

define, with the side rails and the crossbar 30, a 2" x 2" square, a 1" x 2" or a 2" x 3" rectangle. It is thus seen that by combining the crossbars 30 and 40 in various ways within the frame, effective working areas of a large variety of sizes can be readily produced. For example, the various permissible squares and rectangles are diagrammatically illustrated in Fig. 7 in which the frame 10 is designated by the square ABCD, the main crossbar 30 by the lines FG or EH, and the auxiliary crossbar by the lines IK or JL. By arranging the crossbars in the various ways indicated in Fig. 7, squares measuring 4" x 4", 2" x 2", and by utilizing one or more additional, secondary one-inch crossbars, not herein shown in detail but which may be represented by the lines MK, EM, etc., rectangles measuring 1" x 1", 1" x 2", 1" x 3", 1" x 4", 2" x 4" and 3" x 4" can be obtained. Consequently, pieces of fabric of various dimensions can be woven. The adjustment can be quickly and easily made by merely inserting the ends of the crossbars 30 and 40 in the appropriate openings 25 and 32. With the crossbars 30 and 40 in place, the weaving procedure is substantially the same as when they are not employed, the yarn being initially looped around the pins of the appropriate side rails and the crossbars.

It has been explained that the teeth 35 and 41 of the respective crossbars 30 and 40 are similar to the teeth 20 of the frame 10. The teeth 35 and 41 may be provided with single, conical protuberances 44 at their upper ends (Fig. 6) or they may have double protuberances as indicated at 45 and 46, respectively. By this means, the yarn or thread can be looped around the pins to extend in either direction and yet be retained in place. The crossbars can be inserted in the frame 10 in either position to place the single protuberances on the desired side.

The side rails 11, 12, 13 and 14 of the loom frame 10 have been described as being of channel shape. However, rails 48 of solid plastic, such as shown in Fig. 5, can be utilized, in which case narrow openings 49 providing the seats 50 are formed in the plastic material. The rails 48 have integral, upstanding pins or teeth 51 formed with protuberances 52 at their upper ends.

It will be observed from the foregoing that my invention provides an improved hand loom which is efficient in performing its intended function and which is strong and durable, besides being especially pleasing in appearance. Since the device is made entirely from plastic material, it lends itself to mass production molding operations so that it can be made at an exceptionally low cost. The molding pins or teeth, being formed integral with the square loom frame, are made substantially circular in cross section so that the occurrence of sharp edges or corners, which might tend to cut the delicate filaments of the yarn or thread being woven, is entirely avoided. Besides, by making the pins integral with the loom frame, it is unnecessary to mount them on the frame and thus the cost of the article is further reduced. The pins are molded with enlargements or protuberances at their upper ends so that the possibility of inadvertently displacing the loops of yarn from the pins is effectively resisted. As a further feature of improvement, the present loom is made wholly adjustable so that the frame can be divided into working areas of various sizes to enable the weaver to fabricate rectangular pieces of different proportions. In accordance with the invention, the

loom frame is divided by the use of crossbars having weaving pins or teeth and the crossbars are adapted to be mounted in the frame by merely inserting their ends in narrow openings in the sides of the frame. As another feature of the invention, the bottoms of the openings provide seats upon which the ends of the crossbars rest so that friction is not relied upon to retain them in their adjusted positions.

While I have herein shown and described the improved hand loom as embodied in preferred forms of construction, by way of example, it will be obvious that various changes might be made in the structure without departing from the spirit of the invention. Consequently, I do not wish to be limited in this respect, but desire to be afforded the full scope of the appended claims.

I claim as my invention:

1. A hand loom, comprising: a one-piece, molded, rectangular frame having side rails, each of said rails having longitudinally spaced upstanding teeth formed integral therewith, opposite rails of said frame having integral, longitudinally extending support portions disposed inwardly of said teeth and provided with a plurality of horizontal seats; and at least one crossbar having longitudinally spaced, upstanding, integral teeth, said crossbar being insertable within said frame to extend transversely thereacross with its ends resting upon selected seats of opposite side rails of said frame, said side rails being of plastic material and integrally molded and being of substantially channel-shaped cross section, said integral teeth of said rails having laterally and outwardly projecting protuberances at their upper ends, said protuberances extending in planes transverse to said rails.

2. A hand loom as defined in claim 1 in which said teeth are substantially circular in cross section.

3. A hand loom, comprising: a one-piece, molded, rectangular frame having side rails, each of said rails having longitudinally spaced upstanding teeth formed integral therewith, wherein in said side rails are of plastic material and integrally molded and are of substantially channel-shaped cross section, said integral teeth of said rails having laterally and outwardly projecting conical protuberances at their upper ends, said protuberances extending in planes transverse to said rails, opposite rails of said frame having integral, longitudinally extending support portions disposed inwardly of said teeth and provided with a plurality of horizontal seats; and at least one crossbar having longitudinally spaced, upstanding, integral teeth, said crossbar being insertable within said frame to extend transversely thereacross with its ends resting upon selected seats of opposite side rails of said frame.

4. A hand loom, comprising: a one-piece, molded, rectangular frame having side rails, each of said rails having longitudinally spaced upstanding teeth formed integral therewith, wherein in said side rails are of plastic material and integrally molded and are of substantially channel-shaped cross section, portions of said teeth extending down alongside and providing ribs on the outer surfaces of said rails, said ribs being of varying lengths to facilitate counting said teeth, opposite rails of said frame having integral, longitudinally extending support portions disposed inwardly of said teeth and provided with a plurality of horizontal seats; and at least one crossbar having longitudinally spaced, upstand-

ing, integral teeth, said crossbar being insertable within said frame to extend transversely thereacross with its ends resting upon selected seats of opposite side rails of said frame.

5. A hand loom, comprising: a one-piece, molded, rectangular frame having side rails, each of said rails having longitudinally spaced upstanding teeth formed integral therewith, opposite rails of said frame having integral, longitudinally extending support portions disposed inwardly of said teeth and provided with a plurality of horizontal seats; and at least one crossbar having longitudinally spaced, upstanding, integral teeth, said crossbar being insertable within said frame to extend transversely thereacross with its ends resting upon selected seats of opposite side rails of said frame, wherein said crossbar is of molded plastic material having integral teeth, said teeth of said crossbar having laterally projecting protuberances at their upper ends extending normal to the longitudinal plane of said crossbar.

6. A hand loom, comprising: a one-piece, molded, rectangular frame having side rails, each of said rails having longitudinally spaced upstanding teeth formed integral therewith, opposite rails of said frame having integral, longitudinally extending support portions disposed inwardly of said teeth and provided with a plurality of horizontal seats; and at least one crossbar having longitudinally spaced, upstanding, integral teeth, said crossbar being insertable within said frame to extend transversely thereacross with its ends resting upon selected seats of opposite side rails of said frame, wherein said crossbar is of molded plastic material having integral teeth, said teeth of said crossbar having laterally projecting, substantially conical protuberances at their upper ends extending normal to the longitudinal plane of said crossbar.

7. A hand loom, comprising: a one-piece, molded, rectangular frame having side rails, each of said rails having longitudinally spaced upstanding teeth formed integral therewith, opposite rails of said frame having integral, longitudinally extending support portions disposed inwardly of said teeth and provided with a plurality of horizontal seats; and at least one crossbar having longitudinally spaced, upstanding, integral teeth, said crossbar being insertable within said frame to extend transversely thereacross with its ends resting upon selected seats of opposite side rails of said frame, wherein said crossbar is of molded plastic material having integral teeth, said teeth of said crossbar having laterally projecting, substantially conical protuberances at their upper ends extending normal to the longitudinal plane of said crossbar, said teeth of said crossbar being substantially circular in cross section.

8. A hand loom, comprising: a one-piece, molded, rectangular frame having side rails, each of said rails having longitudinally spaced upstanding teeth formed integral therewith, opposite rails of said frame having integral, longitudinally extending support portions disposed inwardly of said teeth and provided with a plurality of horizontal seats; and at least one crossbar having longitudinally spaced, upstanding, integral teeth, said crossbar being insertable within said frame to extend transversely thereacross with its ends resting upon selected seats of opposite side rails of said frame, wherein said crossbar is of molded plastic material having integral teeth, each tooth of said crossbar having a pair of oppositely directed, laterally projecting

protuberances at its upper end extending normal to the longitudinal plane of said crossbar.

9. A hand loom, comprising: a one-piece, molded, rectangular frame having side rails, each of said rails having integral, longitudinally spaced upstanding teeth, opposite rails of said frame each having integral, longitudinally extending support portions disposed inwardly of said teeth and provided with vertical notches, the bottom of each notch providing a horizontal seat; a crossbar having longitudinally spaced, upstanding, integral teeth, said crossbar being insertable within said frame to extend transversely thereacross with its ends disposed in selected notches of opposite side rails and resting upon said seats thereof, said crossbar having at least one vertical notch in at least one side thereof aligned with one of said notches of one of said side rails; and an auxiliary bar having longitudinally spaced, upstanding, integral teeth and insertable within said frame to extend between said crossbar and a side rail parallel to said crossbar with its ends disposed in said aligned notches and resting upon the seats thereof, wherein each of said teeth of said rails, said crossbar and said auxiliary bar is substantially circular in cross section and has at least one laterally projecting, substantially conical protuberance at its upper end.

10. A hand loom, comprising: a one-piece, molded, rectangular frame having side rails, each of said rails having longitudinally spaced upstanding teeth formed integral therewith, opposite rails of said frame having integral, longitudinally extending support portions disposed inwardly of said teeth and provided with a plurality of horizontal seats; and at least one crossbar having longitudinally spaced, upstanding, integral teeth, said crossbar being insertable within said frame to extend transversely thereacross with its ends resting upon selected seats of opposite side rails of said frame, wherein said crossbar is of molded plastic material and is cruciform in cross section.

11. A hand loom, consisting in a one-piece, plastic, rectangular frame having side rails each provided with longitudinally spaced, upstanding, integral teeth, said teeth being substantially circular in cross section and each having at least one laterally projecting, substantially conical, protuberance at its upper end extending normal to the longitudinal plane of the rail.

12. A hand loom comprising: a rectangular

frame having side rails, each of said rails having longitudinally spaced, upstanding teeth formed integral therewith, said teeth having downward integral extensions disposed alongside the outer portions of said rails and providing ribs on the outer surfaces of said rails, said ribs extending downward varying the distances to facilitate counting said teeth.

13. A hand loom comprising: a one-piece, molded, rectangular frame having side rails, each of said rails having longitudinally spaced, upstanding teeth molded integral therewith; and outwardly projecting integral protuberances disposed on the upper end of said teeth to retain yarn looped over said teeth, the width of said protuberances being equal to the width of said teeth, the sides of said teeth directed longitudinally of the respective rails being free from protuberances.

14. A hand loom as in claim 13 wherein inner portions of opposite side rails are provided with vertically disposed retaining recesses, the hand loom including a crossbar whose ends are insertable into said recesses to extend transversely of said frame, said crossbar being provided with spaced upstanding teeth adapted to cooperate with the teeth of one of the side rails from which it is spaced in parallel relation thereto when inserted, the teeth of said crossbar having protuberances extending the full width of said crossbar and projecting away from the protuberances of said cooperating teeth on said one of said side rails, the sides of said crossbar teeth directed longitudinally of the crossbar being free from protuberances.

KEITH J. SMITH.
